United States Patent Office

Des. 224,274
Patented July 11, 1972

224,274

FONT OF TYPE

William Beck, 57B Troy Hills Village, Rte. 46,
Parsippany, N.J. 07054

Filed Oct. 26, 1970, Ser. No. 25,636

Term of patent 3½ years

Int. Cl. D18—04

U.S. Cl. D64—12

FIG. 1

FIG. 1 is a face view of the upper case letters and numerals of a font of type showing my new design; and FIG. 2 is a face view of the lower case letters and punctuation marks thereof.

I claim:

The ornamental design for a font of type, as shown.
